JOHN CROWE, OF ST. JOSEPH, MISSOURI, ASSIGNOR TO SPECIALTY SHOE MACHINERY AND TOOL COMPANY, OF ST. JOSEPH, MISSOURI, A CORPORATION OF MISSOURI.

NAIL-FEED FOR SHOE-NAILING MACHINES.

1,123,252.

Specification of Letters Patent.

Patented Jan. 5, 1915.

Application filed November 29, 1909. Serial No. 530,324.

To all whom it may concern:

Be it known that I, JOHN CROWE, citizen of the United States, residing at St. Joseph, in the county of Buchanan and State of Missouri, have invented certain new and useful Improvements in Nail-Feeds for Shoe-Nailing Machines, of which the following is a specification.

My invention relates to shoe nailing machines and has particular reference to the nail feeding mechanism pertaining to such appliances.

The chief objects of the improvements hereinafter set forth and which constitute the subject matter of this application for patent are:—to provide a positive and efficient nail feeding means whereby the nails presented at the outlet of the supply hopper will be transferred consecutively to the nail sleeve, and to furnish a novel and practical mechanism adapted to seize a single nail and convey it out of the row of descending nails arranged along the inclined channel in the hopper, thus breaking the continuity of the nail line and preventing the deposit of more than one nail at a time in the conduit leading to the cavity of the nailing sleeve.

Other objects of this invention, stated more in detail, are:—to provide a carrier having an automatic gripping device for seizing and retaining the selected nail during its transference; to furnish a positive mechanical movement for dislodging the nail when released from the gripping means, and to furnish means for arresting the descent of the nails arranged in alinement in the hopper channel, during the time of the conveyance of the selected nail to the nail duct or conduit and the return of the carrier to the initial position.

Further objects of the invention are to furnish means for unlocking the hopper to permit it to be rotated in order to bring another receptacle into operative position, and to provide a stop for limiting the upward movement of the carrier on the return stroke of the hammer.

I accomplish the results above stated and others of minor importance by employing the apparatus illustrated in the accompanying drawing, which constitutes a part of this application, the details of construction being shown in the following views:

Figure 1 is a side elevation of my improved nail feeding device attached to an automatic shoe nailing machine, only so much of the latter appliance being shown as will suffice to indicate the manner of mounting and operating said device; Fig. 2 is a front elevation of the structure illustrated in Fig. 1; Fig. 3 is a top plan view showing the carrier in alinement with the hopper, the position of said carrier when dropping a nail being shown in dotted outlines; Fig. 4 is a fragmentary view showing the carrier in vertical section; Fig. 5 is an end elevation of the post and attachments, and Figs. 6 and 7 are a rear elevation of a top plan view, respectively, of the carrier and sleeve.

Referring to the details of the drawing, the numeral 10 indicates the fixed mast of a shoe nailing machine, the upper end only being shown, and 11 the presser arm having a sleeve 12 slidably mounted on said mast and a hollow head 13 in which a nailing sleeve 14 is removably secured by a set screw 15. Located at one side of the presser arm 11, and having a slight inclination therewith is a drive or hammer arm 16, provided at the extremity with a collar 17, arranged above the nailing sleeve 14, the axes of said collar and nailing sleeve being coincident. The said collar 17 carries a cylindrical driver or hammer 18, firmly secured in the collar by a set screw 19. This hammer differs from the ordinary hammer used in nailing machines of this type in being elongated so that it projects to a considerable distance above the collar 17, as shown in the drawing, and is supplied with a head 20, secured on the hammer body by a pin 21, which projects upon one side for a purpose that will be hereinafter explained.

Slidably mounted upon the hammer body above the collar 17 is a nail carrier comprising a sleeve 22 having attached to one side a block 23, preferably cast integral therewith, and furnished with forwardly projecting ears 24, which support a movable jaw 25. A screw 26, passing through said ears and jaw, serves as a pivot upon which the jaw may be moved in a manner to be described. The rear end of the jaw is rectangular in cross section and is provided at the extremity with two transverse ridges or teeth 27, 28, projecting from the upper

and lower surfaces respectively. The lower tooth 28 is received in a corresponding groove 29, formed in the upper surface of the block 23 when the said jaw is in its lowest position relative to the said block, in which case the movable jaw lies in apposition with the upper surface of the block. The rear face of the block 23 is provided with a vertical nail groove 30, of suitable dimensions to receive a single nail of the largest size which the device is adapted to use. The nail body lies in said groove and is suspended therein by the head which rests in the said transverse groove 29, and is held firmly therein by the tooth 28 so long as the said movable jaw 25 is depressed relatively to the block 23. The jaw 25 is constantly urged toward its depressed or closed position by a spring pressed plunger 31, which is arranged in an inclined bore 32, extending partly through the upper end of the fixed jaw or block 23, as shown in Fig. 4. The rear end of the plunger 31 is reduced to form a beak or stem 33, lying in a reduced axial extension of the said bore, which communicates with the nail groove 30. A coiled spring 34 surrounds the stem 33 within the said bore and urges the front end of the plunger against a pendant finger 35 attached to the body of the said jaw 25 thus normally tending to close the jaw down upon the block or main body of the carrier. The said sleeve 22 and attached block 23 are pressed upwardly by a spring 36, which surrounds the hammer body between the said sleeve and the collar 17. The said block is also adapted to swing horizontally about the hammer axis as a center, its movement in one direction being controlled by the spring 36, which has its lower end attached to a pin 37 in the collar 17, and its upper end engaging the block 23 so that the torsional force of the spring will carry the block back to its initial position after it has been swung away from its alignment with the hopper by mechanism hereinafter described. Projecting forward at an angle from the movable jaw 25 is a thumb piece 38, pressure upon which will open the jaw by rocking it upon its pivot 26.

A bracket or post 39 is mounted upon the upper surface of the pressure arm 11, and is secured thereto by a screw 40 passing through a flange or foot 41 integral with said post. A lip or lug 42 projects forward from the upper end of the post, and is received in a notch 43, formed in the rear face of the block 23, (see Fig. 6) when the latter is in its initial position. The upper corner 60 of said lug or lip 42 is rounded to form a cam surface 44, and the upper margin of the notch 43 in the block is correspondingly curved as shown at 45, Fig. 4. The under side of the lug 42 is flat and engages the 65 projection 46 forming the lower side of the

notch 43, when the parts are in alignment, as shown in Fig. 2, and this interlocking of the lips or lugs 42 and 46 limits the upward movement of the sleeve 22, which is continually acted upon by the expansive 70 force of the spring 36. The said sleeve is thus held a short distance below the hammer head 20 during a portion of the hammer movement, as shown in Fig. 2, where the hammer arm is seen at its highest position. When the hammer arrives near the upper end of its stroke the pin 21 will engage the inclined face 46^a of an arm 47, projecting upward from the said jaw 25, and move the said arm sufficiently to open 80 the jaw, this position of the respective parts being shown in Fig. 2. The carrier block 23 has a vertical face 48, the plane of which is radial to the axis of the hammer body about which the block swings. Upon the 85 side of the post 39 is mounted a lever 50, pivotally secured by a shouldered screw 51. Extending upward and forward from the top of this lever is an arm 52, which is offset from the plane of the lever by a recurved 90 bend or loop 53. The said arm is bent outwardly at 54, so that it will clear a pin 69, projecting from the side of the block 23, when the said block is carried downwardly by the action of the hammer arm 16. 95 Near its end the arm is furnished with a tooth 56, and beyond this the extremity is rounded. Upon the rear outer corner of the block 23 is attached a nail duct 57, the upper portion of which has its front wall 100 cut away, as shown at 58 in Fig. 5. The lower end of the duct 57 communicates with the cavity (not shown) in the nailing sleeve by means of a tubular connection 59, the two parts forming what is herein termed 105 the nail conduit.

When the presser arm 11 and the hammer arm 16 are at the upper limit of their strokes, the rear face of the carrier block 23 is in apposition with the discharge end of 110 the supply hopper 60, and the nail groove 30 in said rear face will be in alignment with the discharge channel in said hopper, so that the first or lowest nail in said channel will fall by gravity into the groove 30 when the 115 retaining spring 61, which rests during a portion of the time upon the heads of the nails in the channel to hold them back, is raised. This is effected at the proper time by means of a latch 62, pivoted at 63 to the 120 side of the hopper and resting on a stop pin 64. The said latch is engaged at the point 65 by a corner of the retaining spring 61, and its forward end has a lug 66 adapted to be engaged by the upper tooth 27 of the 125 movable jaw 25 when the hammer and carrier move upward, and as the said jaw 25 is opened by the action of the pin 21, the said latch will be raised, thereby lifting the spring 61 and releasing the nails in the 130

channel so that they are free to move down by gravity toward the outlet. The lever 50 has an extension 67 which moves in a groove between the upper part of the nail duct 57 and the post 39 and upon this extension is a lug 68 which enters the lower part of the nail channel in the hopper to lock the hopper in proper alignment. This form of hopper lock is adapted for use with a rotary type of hopper, only a portion of such a receptacle being shown in the drawing, since it forms no part of the present invention.

The operation of the apparatus is as follows:—When the hammer is at the upper end of its stroke, as shown in Fig. 2, the carrier will be held by the torsion of the spring 36 in the nail receiving position, with the nail groove 30 in alignment with the nail run in the hopper, the jaw 25 held open by the action of the pin 21, and the latch 62 raised by engagement therewith of the tooth 27, while the hopper 60 is locked in operative position by the lug 68. The effect of the engagement of the pin 21 with the arm 47 is to slightly raise the jaw 25 opening it just sufficiently to permit the first nail to drop within the nail groove 30, but not enough to cause the stem 33 of the plunger 31 to enter said groove, which, if it did so, would prevent the entrance of the nail. Should it be desired to shift the revolving hopper in order to bring another receptacle into feeding position, the operator places his thumb upon the piece 38 and depresses it as far as it will go. This will open the jaw 25 to its fullest extent, and cause the stem of the plunger to push the nail, if there is one in the groove, back into the nail run or channel of the hopper. By exerting a little more force upon the thumb piece, the block will be swung upon its center, which is the axis of the hammer, and as it turns a pin 69 upon the side of the block 23 will engage the tooth 56 and rock the lever 50, withdrawing the lug 68 from the nail channel and allowing the hopper to be turned to the desired point, where it is again locked by releasing the thumb piece 38. If the nailing machine mechanism is now operated in the usual manner, the arm 16 will descend, the carrier remaining at rest until the head of the hammer engages the upper end of the sleeve 22. At the beginning of this movement the pin 21 will release the arm 47 and allow the jaw 25 to close down upon the head of the nail in the groove 29, clamping it firmly, at the same time releasing the latch 62 and permitting the retaining spring 61 to clamp the heads of the nails in the hopper channel and hold them back. As the hammer continues on its downward movement, the action of the cam 44 will be to first engage the rounded surface 45 and then swing the block 23 away from the nail receiving position until the rear face of the block is directly in

front of and covering the open part of the nail duct 57, so that the nail groove 30 and said duct are in alignment by the time the said block has reached the end of its downward stroke. In the meantime the presser arm has completed its limited downward movement, and at the completion of the descent of the carrier a pin 70 on the side of the jaw 25 will engage the end of the arm 52 in front of the tooth 56 the said arm acting as a stop to raise the jaw 25 and release the nail, the jaw movement being sufficient to thrust the stem 33 of the plunger 31 entirely across the groove 30 and thus force the nail out of its seat if it should chance to stick, and cause it to fall into the duct 57, whence it passes through the extension 59 into the cavity of the nailing sleeve. Although the projected path of the pin 70 passes considerably to one side of the fulcrum 51, the trend of the curve at the point of impact of the said pin causes the line of force to pass through or above the center and thus prevents the arm from moving.

The movements of the parts upon the up stroke of the hammer are practically the reverse of those above described. At the beginning of the movement the release of the pin 70 from contact with the end of the arm 52 will permit the spring 34 to close the jaw 25 and as the hammer rises the spring 36 will cause the carrier to follow, and the cam 44, riding along the vertical face 48 will hold the carrier from swinging back to its initial position until the notch 43 is reached. The fixed jaw or block 23 will now fly back to the said initial or nail receiving position under the influence of the torsional force of the spring 36, the lug 46 preventing the block from rising higher. The hammer arm continues to ascend until the pin 21, engaging the arm 47, opens the jaw 25, and this lifts the latch 62 to raise the spring 61 and permit another nail to fall into the groove 30.

Having thus described my invention, what I claim as new, is:—

1. In a shoe nailing machine, the combination with a nail receptacle, and nail driving means including a plunger, of nail feeding means comprising a member arranged to oscillate about the axis of said plunger and also to slide longitudinally thereon, a nail grasping device mounted on said member, and means operated by said device for controlling the discharge of nails from said receptacle.

2. In a shoe nailing machine, the combination with a nail receptacle, and nail driving means including a plunger, of nail feeding means comprising a member embracing said plunger and arranged to both oscillate and slide thereon, a nail grasping device arranged on said member, means controlled by the action of said plunger for operating said

- device, and means operated by said grasping device for controlling the discharge of nails from said receptacle.
3. In a shoe nailing machine, the combination with a nail receptacle, and nail driving means including a plunger, of nail feeding means comprising a member arranged to oscillate about the axis of said plunger and also to slide longitudinally thereon, a nail grasping device mounted on said member, and means controlled by the action of said plunger for operating said grasping device.
4. In a shoe nailing machine, the combination with a movable nail receptacle, and nail driving means including a plunger, of nail feeding means comprising a member arranged to oscillate about the axis of said plunger and also to slide longitudinally thereon, a nail grasping device arranged on said member, means controlled by the action of said plunger for operating said device, means operated by said grasping device for controlling the discharge of nails from said receptacle, and means controlled by said member for locking the said receptacle in operative position.
5. In a shoe nailing machine, the combination with a nail receptacle, and nail driving means including a plunger, of nail feeding means comprising a carrier arranged to oscillate about the axis of said plunger, and also to slide relatively thereto, means on said receptacle for controlling the discharge of nails therefrom, and a nail grasping member comprising a movable jaw pivoted on said carrier, said jaw being adapted to operate the said controlling means for the discharge of nails from the receptacle.
6. In a shoe nailing machine, the combination with a nail receptacle, and nail driving means including a plunger, of nail feeding means comprising a carrier pivotally supported on said plunger, and arranged to slide longitudinally thereon, a spring arranged to move said carrier both horizontally and vertically on its pivot, a nail gripping device mounted on said carrier; and means operated by said device for controlling the discharge of nails from the receptacle.
7. In a shoe nailing machine, the combination with a nail receptacle, and nail driving means including a plunger, of nail feeding means comprising a carrier mounted upon said plunger and arranged to oscillate and also to slide thereon, a spring arranged to operate the carrier by both its torsional and expansive action, a nail gripping jaw mounted on said carrier; means on said plunger for operating said jaw, and means operated by said jaw for controlling the discharge of nails from the receptacle.
8. In a shoe nailing machine, the combination with a nail receptacle, and nail driving means including a hammer, of a nail
- carrier arranged to slide longitudinally on the said hammer and also to swing about the axis of the hammer.
9. In a shoe nailing machine, the combination with a nail receptacle, a drive arm, a hammer carried by said drive arm, and a presser arm coöperating with said drive arm, of a nail carrier slidably and pivotally mounted on said hammer, means on said presser arm for sliding said carrier, and means for turning said carrier about the axis of the hammer.
10. In a shoe nailing machine, the combination with a nail receptacle, a drive arm, a hammer mounted in said arm, and a presser arm, of a block mounted to slide and turn on said hammer, a movable jaw pivoted on said block, means on said hammer for operating said jaw, means on said presser arm for turning said block, and means on said hammer for causing the block to move therewith.
11. In a shoe nailing machine, the combination with a nail receptacle, a drive arm, a hammer mounted in said arm, and a presser arm, of a sleeve mounted to slide and swing on said hammer, a spring for the sleeve, a block attached to said sleeve, a movable jaw on said block, means on said hammer for operating said jaw, means on said presser arm for swinging said block in one direction, and means on said hammer engaging said sleeve to depress the block relatively to said nail receptacle.
12. In a shoe nailing machine, the combination with a nail receptacle, a drive arm, a hammer carried by said arm, a presser arm and a nailing sleeve mounted on said presser arm, of a nail gripping device mounted to slide and swing upon said hammer, means carried by said presser arm for swinging said device in one direction, means carried by the hammer for swinging the device in the opposite direction, and means on the hammer for moving the said device relative to the nailing sleeve.
13. In a shoe nailing machine, the combination with a nail hopper, a drive arm, a hammer carried by said arm and a presser arm, of a nail carrier adapted to slide and turn upon said hammer, a movable jaw on said carrier, means for swinging the carrier into and out of operative position relative to the hopper, means on the hammer arranged to reciprocate the carrier, and means for automatically opening said movable jaw when said carrier is at either end of its reciprocating movement.
14. In a shoe nailing machine, the combination with a nail hopper, a nail retaining spring on the hopper, a drive arm, and a hammer carried by said arm, of a nail carrier arranged to slide and swing upon said hammer, a movable jaw on said carrier, means on the hammer arranged to recipro- 125

cate said carrier, means for opening said jaw when the carrier is at either limit of its reciprocating movement, and means on the hopper arranged in the path of said jaw for retracting said nail retaining spring.

5 15. In a shoe nailing machine, the combination with a nail hopper, having a nail run therein, a nail retaining spring on the hopper, a drive arm, a hammer, and a presser arm, of a nail carrier adapted to slide and swing upon said hammer, said carrier having a nail groove adapted to be brought into alinement with said nail run, a movable jaw on the carrier adapted to 10 grasp the head of a nail when engaging said groove, means for swinging said carrier so as to move the nail groove into and out of alinement with the nail run, means carried by the hammer for reciprocating 15 the carrier, means for opening the jaw when in its lowest position, and means for dislodging the nail from said groove by the opening movement of said jaw.

16. In a nail feeding device, the combination with a hopper provided with a discharge aperture, and a nailing sleeve, of a nail conduit communicating with the cavity of said sleeve and arranged out of alinement with the discharge aperture in the hopper, 20 and means for conveying the nails consecutively from the discharge aperture to said conduit, said means comprising a carrier arranged to rotate on a center coincident with the axis of the hammer, a nail gripping device mounted on said carrier, and means operated by said device for controlling said discharge aperture.

17. In a nail feeding device, the combination with a hopper provided with a discharge aperture, and a nailing sleeve, of a nail conduit communicating with the cavity 25 of said sleeve and having its upper end

open and arranged so as to leave an interval between said open end and the discharge aperture in the nail hopper, a carrier adapted to convey the nails from the discharge aperture to the conduit, a nail groove in said carrier, and a plunger adapted to be projected into said groove to discharge the nail held therein.

50 18. In a nail feeding device, the combination with a nail hopper provided with a discharge aperture, and a nailing sleeve, of a nail conduit communicating at one end with the cavity of the said sleeve and having the other end arranged at a distance from the said discharge aperture, a nail carrier arranged to convey the nails consecutively from the hopper to the said nail conduit, and means for removing the nail from the carrier when in apposition with said conduit, said means comprising a spring held plunger arranged in a suitable aperture in said carrier and adapted to engage a nail held in the carrier.

65 19. In a nail feeding device, the combination with a nail hopper, a nail discharge channel therefor, a nailing sleeve, and a nail conduit communicating with said sleeve, of means for conveying nails consecutively 70 from the discharge channel to the conduit, said means comprising a member arranged to both oscillate and reciprocate, a nail groove in said member, a gripping device for retaining a nail in said groove, means 75 for dislodging a nail from the groove, and means operated by the gripping device for controlling the said discharge channel.

In testimony whereof I affix my signature in the presence of two witnesses.

JOHN CROWE.
